[57] CLAIM

The ornamental design for a fishing lure, as shown and described.

DESCRIPTION

FIG. 1 is a perspective view of a fishing lure according to my invention;

FIG. 2 is a top plan view thereof;

FIG. 3 is a view of the side of my invention not shown in FIG. 1;

FIG. 4 is a front end view thereof;

FIG. 5 is a rear end view thereof; and

FIG. 6 is a bottom plan view thereof.

The fishhooks have been omitted from FIGS. 2 thru 6 for convenience of illustration only.
